CLAIM

The ornamental design for a disposer fluid injection assembly, as shown and described.

DESCRIPTION

FIG. 1 is a front perspective view of the disposer fluid injection assembly;

FIG. 2 is a front elevational view of the disposer fluid injection assembly;

FIG. 3 is a rear elevational view of the disposer fluid injection assembly;

FIG. 4 is a right side elevational view of the disposer fluid injection assembly;

FIG. 5 is a left side elevational view of the disposer fluid injection assembly;

FIG. 6 is a top plan view of the disposer fluid injection assembly;

FIG. 7 is a bottom plan view of the disposer fluid injection assembly; and,

FIG. 8 is an exploded view of the disposer fluid injection assembly.

The features shown in broken lines in FIGS. 1-8 illustrate environmental features that form no part of the claimed design.
